(57) **ABSTRACT**

A deflection correction device includes a first rod-like member provided in stringed instrument necks; fixing members attached to end parts of the first rod-like member; a screw hole formed so as to pass through the fixing member; and a second rod-like member provided with a screw shaft part screwed in the screw hole, and attached to the fixing member. The fixing members includes fitting grooves fitted on the end parts of the first rod-like member; shaft holes passing through the end parts of the first rod-like member from side surfaces of the fixing members; and a shaft member inserted in the screw holes. The fixing members are fixed to the end parts of the first rod-like member together with the shaft member, and by rotation of the second rod-like

(Continued)

member, both the fixing members are pushed in a direction drawn to or away from each other.

DEFLECTION CORRECTION DEVICE FOR STRINGED INSTRUMENT NECKS

RELATED APPLICATIONS

The present application is National Phase of International Application No. PCT/JP2022/021230 filed May 24, 2022, and claims priority from Japanese Application No. 2021-172419, filed Oct. 21, 2021, the disclosure of which is hereby incorporated by reference herein in its entirety.

TECHNICAL FIELD

The present invention relates to a deflection correction device for stringed instrument necks which device corrects neck deflection caused by strings or the like in stringed instruments such as a guitar, a base guitar, a ukulele, a violin, a cello, a mandolin and a contrabass.

BACKGROUND ART

In a stringed instrument such as a guitar, a base guitar, a ukulele, a violin, a cello, a mandolin or a contrabass, when the instrument is stringed, the neck readily deflects toward the front side of the instrument because of the tension of the strings or the like. To correct such neck deflection, a deflection correction device is embedded in the neck in the direction of the length thereof.

In a typical deflection correction device, by combining two rod-like members and increasing or decreasing the length of one rod-like member by the action of a screw, the other rod-like member is bent concavely or convexly so that this deflection of the rod-like member offsets the deflection of the neck caused by the tension of the stings or the like.

For example, in a neck deflection correction device described in Patent Literature 1, as shown in FIGS. 1A to 1D of Patent Literature 1, a block-like fixing member 20 is attached to the base end part of a first rod-like member 12 by bonding or the like, and a first male screw 25t of a screw member 25 is screwed in the opposite direction of a second rod-like member 14 into a screw hole (first female screw 22w) formed so as to pass through the fixing member 20.

Moreover, a second male screw $14t$ of the second rod-like member 14 is screwed in a second female screw $25w$ formed in the first male screw $25t$. As shown in FIGS. 1A and 1C, the second rod-like member 14 is slightly curved in advance. The neck deflection correction device 10 having the above-described structure is embedded in a long groove $2s$ of a neck 2 . Then, by rotating the screw member 25 in a loosening direction, the second rod-like member 14 is pulled to deflect the first rod-like member 12 convexly as shown in FIG. 1B, and by rotating the screw member 25 in a tightening direction, the second rod-like member 14 is pushed in a compressing direction to deflect the first rod-like member 12 concavely as shown in FIG. 1D. For this reason, the deflection of the neck 2 by a string 4 can be corrected by adjusting the degree of the concave curve or the convex curve of the first rod-like member 12 .

CITATION LIST

Patent Literature

2

DISCLOSURE OF THE INVENTION

Problem to be Solved by the Invention

- 5 However, in the conventional neck deflection correction device as described in Patent Literature 1, since the fixing member 20 coupling the first rod-like member 12 and the second rod-like member 14 is attached to the base end part of the first rod-like member 12 by bonding or the like, the
10 bonding or the like between the fixing member 20 and the base end part of the first rod-like member 12 is readily peeled off after repeated corrections by rotating the screw member 25. While it is considered to attach the fixing member 20 and the base end part of the first rod-like member
15 12 by welding or brazing instead of bonding or the like, in either case, if the bonded part, the welded part or the brazed part is broken by repeated loading, the neck deflection correction device becomes non-functional, which makes it necessary to replace the deflection correction device.
20 However, it is not easy to replace the deflection correction device embedded in the neck and it is necessary to disassemble the neck or the stringed instrument itself, which requires an excessive amount of time and cost. For this reason, the life of the deflection correction device is required
25 to be as long as possible, and is considered ideal if it is as long as the life of the stringed instrument.
Moreover, while the deflection correction device described in Patent Literature 1 is capable of correcting deflection in one direction, that is, deflection where the neck
30 is curved upward by the tension of the strings or the like (hereinafter, referred to as convex deflection), it is incapable of correcting deflection where the neck is curved downward (hereinafter, referred to as concave deflection).
The present invention is made in view of requirements
35 and problems as described above, and an object thereof is to provide a deflection correction device in which the coupling of the two rod-like members is made firmer, the fixed parts such as the bonded, welded or brazed parts do not readily break, even if these fixed parts break, the need for replacement does not arise over a long period of time by maintaining the coupling of the two rod-like members over a pre-determined period of time and both the concave and convex deflections can be corrected.
45 Means for Solving the Problem
To attain the above-mentioned object, a deflection correction device of the present invention is, as recited in claim 1, provided with in a deflection correction device that
50 corrects deflection of a neck of a stringed instrument: a first rod-like member provided in a length direction of the neck; one end side fixing member attached to one end side of the first rod-like member and the other end side fixing member attached to the other end side thereof; a screw hole formed
55 so as to pass through the other end side fixing member; and a second rod-like member provided along the first rod-like member, provided with a screw shaft part screwed in the screw hole on the other end side, and having one end part thereof attached to the one end side fixing member, the one
60 end side fixing member and the other end side fixing member are provided with: fitting grooves fitted on the one end part and the other end part of the first rod-like member; shaft holes passing through the one end part and the other end part of the first rod-like member from side surfaces of
65 the one end side fixing member and the other end side fixing member; and a shaft member inserted in the shaft holes, the one end side fixing member and the other end side fixing member.

Means for Solving the Problem

To attain the above-mentioned object, a deflection correction device of the present invention is, as recited in claim 1, provided with in a deflection correction device that corrects deflection of a neck of a stringed instrument: a first rod-like member provided in a length direction of the neck; one end side fixing member attached to one end side of the first rod-like member and the other end side fixing member attached to the other end side thereof; a screw hole formed 50 so as to pass through the other end side fixing member; and a second rod-like member provided along the first rod-like member, provided with a screw shaft part screwed in the screw hole on the other end side, and having one end part thereof attached to the one end side fixing member, the one 55 end side fixing member and the other end side fixing member are provided with: fitting grooves fitted on the one end part and the other end part of the first rod-like member; shaft holes passing through the one end part and the other end part of the first rod-like member from side surfaces of 60 the one end side fixing member and the other end side fixing member; and a shaft member inserted in the shaft holes, the one end side fixing member and the other end side fixing 65 member; and a shaft member inserted in the shaft holes, the one end side fixing member and the other end side fixing member;

member are fixed to the one end part and the other end part together with the shaft member, and by the screwing between the screw hole and the screw shaft part accompanying rotation of the second rod-like member, the one end side fixing member and the other end side fixing member are pushed in a direction in which they are drawn to each other or in a direction in which they are moved away from each other.

As recited in claim 2, the one end part and the other end part of the first rod-like member are formed to be angular in cross section, and the fitting grooves of the one end side fixing member and the other end side fixing member are formed in a U shape that is fitted on the one end part and the other end part, which enables the one end side fixing member and the other end side fixing member to be fixed to the first rod-like member more firmly.

As recited in claim 3, the following may be performed: A screw hole is formed on the one end side fixing member, a screw part is formed on the one end part of the second rod-like member, and the second rod-like member is screwed in the screw hole of the one end side fixing member. By doing this, the load that moves the one end side fixing member and the other end side fixing member in a direction in which they are drawn to each other or in a direction in which they are moved away from each other which load is caused by the screwing between the screw shaft part or the screw part and the screw hole occurring when the second rod-like member is rotated can be distributed to the other end side fixing member and the one end side fixing member. Moreover, the displacement amount at the part where the screw shaft part or the screw part and the screw hole are screwed can also be distributed to the other end side fixing member and the one end side fixing member. Consequently, the breakage of the parts where the one end side fixing member and the other end side fixing member, and the first rod-like member are fixed can be suppressed over a longer period of time.

As recited in claim 4, the following may be performed: The second rod-like member is divided into at least two of a first part and a second part, the first part and the second part are coupled by a coupling member, one end part of the first part is coupled to the one end side fixing member, and the second part where the screw shaft part is formed is screwed in the screw hole of the other end side fixing member.

By doing this, the attachment of the second part to the first part is facilitated.

In this case, as recited in claim 5, the following may be performed: One end part of the first part is fixed to the one end side fixing member, and a screw part is formed on the other end part of the first part and is screwed in a screw hole on one end side of the coupling member. Moreover, as recited in claim 6, the following may be performed: A screw part is formed on one end part of the first part and is screwed in the screw hole formed on the one end side fixing member, the other end part of the first part is fixed to one end side of the coupling member, and the screw shaft part of the second part is screwed in the screw hole of the other end side fixing member. Moreover, as recited in claim 7, the following may be performed: One end part of the first part is fixed to the one end side fixing member, the other end part of the first part is fixed to one end side of the coupling member, and one end part of the screw shaft part of the second part is screwed in a screw hole formed on the other end side of the coupling member.

With the structure as recited in claims 5 to 7, by rotating the second part, not only the second part is moved back and forth by the screwing between the screw shaft part of the

second part and the screw hole of the other end side fixing member but also by the screwing between the screw part of the other end part of the first part and the screw hole of the coupling member, the screwing between the screw part of the one end part of the first part and the screw hole of the one end side fixing member or the screwing between the screw shaft part of the second part and the screw hole of the coupling member, the load that moves the one end side fixing member and the other end side fixing member in a direction in which they are drawn to each other or in a direction in which they are moved away from each other can be distributed to two parts and the displacement amount can also be distributed to two parts. Consequently, the breakage of the parts where the one end side fixing member and the other end side fixing member, and the first rod-like member are fixed can be suppressed over a longer period of time.

Further, as recited in claim 8, a covering member that prevents the first rod-like member and the second rod-like member from being in contact with each other is formed on at least one of the first rod-like member and the second rod-like member.

By forming such a covering member, abnormal noise can be prevented from being caused by the first rod-like member and the second rod-like member made of a metal being in contact with each other when the instrument is played.

Advantageous Effects of the Invention

Since the present invention is structured as described above, not only a convex deflection but also a concave deflection can be corrected. Moreover, the parts where the first rod-like member and the one end side and other end side fixing members are fixed do not readily break, so that the life of the deflection correction device can be further increased. Further, even if the fixing parts break, since the coupling between the first rod-like member and the second rod-like member can be maintained by the shaft member, the life of the deflection correction device can be further increased.

Moreover, by rotating the second rod-like member, the load acting on the one end side fixing member and the other end side fixing member on both ends, and the displacement amount are distributed to two parts, so that the life of the deflection correction device can be further increased.

As described above, according to the present invention, a deflection correction device can be provided that is capable of correcting not only a convex deflection but also a concave deflection and has the life as long as the life of the musical instrument.

BEST MODE FOR CARRYING OUT THE INVENTION

Hereinafter, a preferred embodiment of a deflection correction device of the present invention will be described in detail with reference to the drawings.

FIGS. 1 to 6 are related to the embodiment of the deflection correction device of the present invention, and FIG. 1 is an assembly front view of the deflection correction device. FIGS. 2A to 6 are explanatory views of components of the deflection correction device of FIG. 1. FIGS. 2A to 2C are related to a first rod-like member, FIG. 2A is a plan view thereof, FIG. 2B is a front view thereof, and FIG. 2C is an enlarged right side view thereof, FIG. 3 is a front view of a second rod-like member, FIG. 4 is a front view of a sleeve, FIGS. 5A and 5B are related to fixing members, FIG. 5A is a side view thereof, FIG. 5B is a front view thereof, and FIG. 6 is a side view of a shaft member.

In the following description, "one end side" indicates the right side of FIG. 1, whereas "the other end side" indicates the left side of FIG. 1.

[First Rod-Like Member 11]

The deflection correction device 1 is formed of a combination of a first rod-like member 11 and a second rod-like member 12, and concavely or convexly deflects the first rod-like member 11 by adjusting the length of the second rod-like member 12 relative to the first rod-like member 11 so as to be longer or shorter, thereby correcting neck deflection.

The first rod-like member 11 has, as shown in FIGS. 2A to 2C, a rod-like body part 111 being angular in cross section, one end part 112 being angular in cross section and formed so as to protrude on one end (the right side end in the figures) of the body part 111, and the other end part 113 being angular in cross section and formed so as to protrude on the other end (the left side end in the figures) of the body part 111. While the first rod-like member 11 may be made of a metal such as stainless steel or steel, it is preferably made of a titanium alloy (for example, 15-3-3-3 titanium alloy).

As shown in FIGS. 2A to 2C, the one end part 112 and the other end part 113 of the first rod-like member 11 are narrower than the body part 111, and are fitted in U-shaped grooves 13c and 14c of fixing members 13 and 14 described later.

On the body part 111, a plurality of holes 111a is formed in the length direction for the purpose of weight reduction and adjustment of the ease of deflection and the deflection form. On the side surfaces of the one end part 112 and the other end part 113, shaft holes 112a and 113a in which a shaft member 16 described later is inserted are formed so as to pass through.

[Second Rod-Like Member 12 and Sleeve 15]

The second rod-like member 12 is, as shown in FIG. 3, divided into a first part 121 on one end side (the right side of the figure) and a second part 122 on the other end side (the left side of the figure). The first part 121 and the second part 122 each have a round bar shape. While the first part 121 and the second part 122 may be made of a metal such as stainless steel or steel, they are preferably made of a titanium alloy (for example, 64 titanium alloy).

On both ends of the first part 121, screw parts 121a and 121b are formed.

The entire length of the second part 122 is formed as a screw shaft part 122a, and on the other end side of the screw shaft part 122a, a head part 122b having a wrench hole 122c is formed.

The first part 121 and the second part 122 are coupled by a sleeve 15 as a coupling member shown in FIG. 4. The sleeve 15 may be made of a metal such as stainless steel, steel, titanium alloy or pure titanium.

The sleeve 15 has a screw hole 15a formed on one end side and has a screw hole 15b formed on the other end side. The screw part 121b on the other end side of the first part 121 is screwed into the screw hole 15a of the sleeve 15, and one end of the screw shaft part 122a of the second part 122 is screwed into the screw hole 15b, whereby the first part 121 and the second part 122 are coupled through the sleeve 15.

On either one of the first rod-like member 11 and the second rod-like member 12 having the above-described structure, in order to prevent abnormal noise from being caused by contact when the instrument is played, at least a part that can be in contact is preferably covered with a resin or the like.

[Fixing Members 13 and 14 and Shaft Member 16]

To the one end part 112 of the first rod-like member 11, one end side fixing member 13 is attached, and to the other end part 113 thereof, the other end side fixing member 14 is attached. In this embodiment, since the one end side fixing member 13 and the other end side fixing member 14 have the same shape, the same size and the same structure, these will be explained as the fixing members 13 and 14 in the following description.

10 While the sleeve 15 may be made of a metal such as stainless steel, steel or titanium alloy, the fixing members 13 and 14 are preferably made of pure titanium.

As shown in FIG. 5A, the grooves 13c and 14c being U-shaped in side view are formed, and these U-shaped grooves 13c and 14c are fitted on the one end part 112 and the other end part 113 of the first rod-like member 11 formed in angular shape. Moreover, screw holes 13a and 14a are formed from one end surfaces toward the other end surfaces of the fixing members 13 and 14 so that the screw shaft part 20 122a of the second part 122 can be screwed therein.

Further, screw holes 13b and 14b in which the shaft member 16 is inserted so as to cross the U-shaped grooves 13c and 14c are formed so as to pass through in a direction intersecting the screw holes 13a and 14a.

25 [Coupling Structure of First Part 121, Second Part 122, Sleeve 15 and Fixing Member 13]

Regarding the parts indicated by the dot-and-dash-line circles of reference designations I, II and III of FIG. 1, reference designation I indicates the part where one end part 30 of the first part 121 and the fixing member 13 are coupled, reference designation II indicates the part where the other end part of the first part 121 and one end part of the sleeve 15 are coupled, and reference designation III indicates the part where one end part of the screw shaft part 122a of the 35 second part 122 and the other end part of the sleeve 15 are coupled.

The screw parts 121a and 121b are formed on both ends of the first part 121, the screw hole 13a is formed on the fixing member 13, the screw holes 15a and 15b are formed 40 on both ends of the sleeve 15, and the screw parts 121a and 121b and the screw shaft part 122a can be screwed into the screw holes 13a, 15a and 15b.

Under a condition where the above-mentioned components are screwed, in the part indicated by reference designation II and the part indicated by reference designation III, the first part 121 and the sleeve 15, and the second part 122 and the sleeve 15 are fixed by brazing, welding or the like; then, the rotation of the second part is transmitted to the first member 121 through the sleeve 15 to move the first part 121 50 screwed in the screw hole 13a of the fixing member 13 by the screw part 121a, back and forth with respect to the fixing member 13.

According to this coupling structure, by rotating the second rod-like member 12, the part that moves back and forth by the screwing is two of the part where the fixing member 14 and the screw shaft part 122a of the second part 122 are screwed and the part indicated by reference designation I, so that the load and the displacement amount at the time of the back-and-forth movement are distributed to two 60 parts.

In the part indicated by reference designation I and the part indicated by reference designation III, the first part 121 and the fixing member 13, and the second part 122 and the sleeve 15 are fixed by brazing, welding or the like; then, the rotation of the second part is transmitted to the sleeve 15 to move the first part 121 screwed in the screw hole 15a by the screw part 121b, back and forth with respect to the sleeve 15.

In the part indicated by reference designation I and the part indicated by reference II, the first part **121** and the fixing member **13**, and the sleeve **15** are fixed by brazing, welding or the like; then, by the rotation of the second part, the second member **122** screwed in the screw hole **15b** of the sleeve **15** by the screw shaft part **122a** is moved back and forth with respect to the sleeve **15**.

With the coupling structure as described above, the second rod-like member **12** is increased or decreased in length by rotation. In this coupling structure, by rotating the second rod-like member **12**, the part that moves back and forth by the screwing is also two of the part where the fixing member **14** and the screw shaft part **122a** of the second part **122** are screwed and the part indicated by reference designation II or the part indicated by reference designation III, so that the load and the displacement amount at the time of the back-and-forth movement are distributed to two parts.

The distribution of the load and the displacement amount at the time of the back-and-forth movement reduces the load acting on the parts where the fixing members **13** and **14** and the first rod-like member **11** are fixed, and makes the fixing parts not readily break, whereby the life of the deflection correction device **1** can be further increased.

[Assembly of Deflection Correction Device **1**]

The deflection correction device **1** shown in FIG. 1 is formed by combining the components shown in FIGS. 2A to 6 by the following procedure.

First, the groove **13c** of the fixing member **13** is fitted on the one end part **112** of the first rod-like member **11**, and the groove **14c** of the fixing member **14** is fitted on the other end part **113**. Then, the shaft member **16** is inserted into the shaft holes **13b**, **112a**, **14b** and **113a** to couple the fixing members **13** and **14** to both ends of the first rod-like member **11**. Thereafter, both ends of the first rod-like member **11**, and the fixing members **13** and **14** and the shaft member **16** are fixed by brazing, welding or the like.

Then, the screw part **121a** on one end side of the first part **121** of the second rod-like member **12** is screwed into the screw hole **13a** of the fixing member **13**, and the screw part **121b** on the other end side is screwed into the screw hole **15a** of the sleeve **15**. The screw shaft part **122a** of the second part **122** is screwed into the screw hole **14a** of the fixing member **14**, and one end of the screw shaft part **122a** is screwed into the screw hole **15b** of the sleeve **15**.

The structure of coupling of the first part **121**, the second part **122**, the sleeve **15** and the fixing member **13** and the action thereof are as described with reference to reference designations I, II and III.

[Action of Deflection Correction Device **1**]

The deflection correction device **1** assembled as described above works as follows:

A non-illustrated wrench is inserted into the wrench hole **122c** (see FIG. 3) of the head part **122b** of the second rod-like member **12** and rotated clockwise; then, by the screwing of the screw shaft part **122a** and the screw hole **14a** of the fixing member **14**, the second part **122** of the second rod-like member **12** moves to one end side (the right side of the figure) to push the two fixing members **13** and **14** so as to move away from each other.

Moreover, the sleeve **15** rotates together with the second part **122** to let the screw part **121b** of the first part **121** out from the screw hole **15a** of sleeve **15**, which also pushes the two fixing members **13** and **14** so as to move away from each other. Thereby, the first rod-like member **11** curves in an upwardly convex direction.

When the wrench is rotated counterclockwise, the first rod-like member **11** curves in a downwardly concave direction by an action opposite to the above-described one.

In the deflection correction device **1** of the present invention, since the fixing members **13** and **14** and both ends of the first rod-like member **11** are present as the structure where the one end part **112** and the other end part **113** having the same structure and the grooves **13c** and **14c** are fitted, even if deflection deformation is repeated, the load acting on the fixing parts of both is comparatively low, so that the life of the fixing parts can be increased. In addition, even if the fixing parts break due to fatigue, since both are coupled by the shaft member **16**, the first rod-like member **11** and the second rod-like member **12** never separate immediately, which also enables the life of the deflection correction device **1** to further increase.

Moreover, by providing the structure where the second rod-like member **12** increases or decreases in length and making the load and the displacement amount distributed at both of the two fixing members **13** and **14**, the fatigue breakage of the fixing parts can be suppressed over a long period of time, so that the life of the deflection correction device **1** can be further increased.

While a preferred embodiment of the present invention has been described, the present invention is not limited to the above-described one.

For example, while the second rod-like member **12** is divided into two parts and the first part **121** and the second part **122** are coupled by the sleeve **15** as a coupling member in the above description, for example, when the second rod-like member **12** can be assembled to the first rod-like member **11** through the fixing members **13** and **14** without being divided, it is not necessarily divided.

Moreover, while the screw hole **13a** is formed on the fixing member **13** on one end side, the screw part **121a** is formed on one end side of the second rod-like member **12** and these are screwed in the above description, when it is necessary to correct only either one of the convex and concave deflections, such screwing is not always necessary; for example, a structure may be adopted in which a hole is formed on the fixing member **13** and one end part of the second rod-like member **12** is inserted therein. In this case, a structure may be adopted in which the hole is bottomed so that one end of the second rod-like member **12** abuts on the bottom of the hole or in which the hole is a through hole so that one end part of the second rod-like member **12** partly protrudes from the through hole and the protruding part is, for example, crushed to prevent escape from the through hole.

INDUSTRIAL APPLICABILITY

The present invention is applicable to a wide range as a deflection correction device not only for a guitar, a base guitar, a ukulele, a violin, a cello, a mandolin and a contrabass but also for other stringed instruments, and is applicable to correction of deflection of not only the neck but also the body part and other parts and to correction of deflection of musical instruments other than stringed instruments. Further, the deflection correction device of the present invention is applicable to correction of not only the deflection due to a physical load such as the tension of the strings but also deflections due to changes in humidity, temperature, climate and the like.

BRIEF DESCRIPTION OF THE DRAWINGS

FIG. 1 is an assembly front view of the deflection correction device.

FIGS. 2A to 2C are related to the first rod-like member, FIG. 2A is a plan view thereof, FIG. 2B is a front view thereof, and FIG. 2C is an enlarged right side view thereof.

FIG. 3 is a front view of the second rod-like member.

FIG. 4 is a front view of the sleeve.

FIGS. 5A and 5B are related to the fixing members, FIG. 5A is a side view thereof, and FIG. 5B is a front view thereof.

FIG. 6 is a side view of the shaft member.

DESCRIPTION OF THE REFERENCE NUMERALS

- 1 Deflection correction device
- 11 First rod-like member
- 111 Body part
- 111a Hole
- 112 One end part
- 112a Shaft hole
- 113 Other end part
- 113a Shaft hole
- 12 Second rod-like member
- 121 First part
- 121a Screw part (one end side)
- 121b Screw part (the other end side)
- 122 Second part
- 122a Screw shaft part
- 122b Head part
- 112c Wrench hole
- 13, 14 Fixing member
- 13a, 14a Screw hole
- 13b, 14b Shaft hole
- 13c, 14c Groove
- 15 Sleeve
- 15a Screw hole (one end side)
- 15b Screw hole (the other end side)
- 16 Shaft member

The invention claimed is:

1. A neck deflection correction device for a stringed instrument, for correcting deflection of a neck of the stringed instrument, comprising:

a first rod-like member provided in a length direction of the neck;
one end side fixing member attached to one end side of the first rod-like member and another end side fixing member attached to another end side of the first rod-like member opposite to the one end side;
a screw hole formed so as to pass through the another end side fixing member; and
a second rod-like member provided along the first rod-like member, and having a screw shaft part screwed in the screw hole on the another end side, and one end part thereof attached to the one end side fixing member, wherein the one end side fixing member and the another end side fixing member include fitting grooves fitted on one end part and another end part of the first rod-like member; shaft holes passing through the one end part and the another end part of the first rod-like member from side surfaces of the one end side fixing member and the another end side fixing member; and shaft members inserted in the shaft holes,
the one end side fixing member and the another end side fixing member are fixed to the one end part and the another end part together with the shaft members, and

by screwing between the screw hole and the screw shaft part accompanying rotation of the second rod-like member, the one end side fixing member and the another end side fixing member are pushed in a direction such that the one end side fixing member and the another end side fixing member are drawn to each other or in a direction such that the one end side fixing member and the another end side fixing member are moved away from each other.

10 2. The neck deflection correction device for stringed instruments according to claim 1, wherein the one end part and the another end part of the first rod-like member are formed to be angular in cross section, and the fitting grooves of the one end side fixing member and the another end side fixing member are formed in a U shape that is fitted on the one end part and the another end part.

15 3. The neck deflection correction device for stringed instruments according to claim 1, wherein a screw hole is formed on the one end side fixing member, a screw part is formed on the one end part of the second rod-like member,

20 the second rod-like member is screwed in the screw hole of the one end side fixing member, and by rotation of the second rod-like member, the one end side fixing member and the another end side fixing member are pushed in a direction such that the one end side fixing member and the another end side fixing member are drawn to each other or in a direction such that the one end side fixing member and the another end side fixing member are moved away from each other in cooperation with the screw hole of the another end side fixing member.

25 30 4. The neck deflection correction device for stringed instruments according to claim 1, wherein the second rod-like member is divided into a first part on one end side and a second part on another end side thereof, the first part and the second part are coupled by a coupling member, one end part of the first part is coupled to the one end side fixing member, and the second part where the screw shaft part is formed is screwed in the screw hole of the another end side fixing member.

35 40 5. The neck deflection correction device for stringed instruments according to claim 4, wherein the one end part of the first part is fixed to the one end side fixing member, and a screw part is formed on another end part of the first part and is screwed in a screw hole on one end side of the coupling member.

45 50 6. The neck deflection correction device for stringed instruments according to claim 4, wherein a screw part is formed on the one end part of the first part and is screwed in the screw hole formed on the one end side fixing member, and another end part of the first part is fixed to one end side of the coupling member.

55 60 7. The neck deflection correction device for stringed instruments according to claim 4, wherein the one end part of the first part is fixed to the one end side fixing member, another end part of the first part is fixed to one end side of the coupling member, and one end part of the screw shaft part of the second part is screwed in a screw hole formed on another end side of the coupling member.

8. The neck deflection correction device according to claim 1, wherein a covering member that prevents the first rod-like member and the second rod-like member from being in contact with each other is formed on at least one of the first rod-like member and the second rod-like member.
